UNITED STATES PATENT OFFICE

ROBERT E. BROWN, OF OLEAN, NEW YORK

POCKETKNIFE

Application filed August 3, 1931. Serial No. 554,900.

This invention relates to cutlery and more particularly to a pocket knife having a handle and blades pivotally mounted for movement into and out of a closed position. At the present time pocket knives have their blades yieldably held in an opened or a closed position by a spring which extends longitudinally between side plates of the handle along the back thereof with its ends engaging the heels and dirt from entering end portions of the knife handle.

The invention is illustrated in the accompanying drawing wherein:

Figure 1 is a view showing a knife of the improved construction in side elevation with one of the face plates removed and the securing pins for the facing plates shown in section.

Figure 2 is a sectional view taken longitudinally through the knife along the line 2—2 of Figure 1, and

Figure 3 is a perspective view of one of the resilient side plates which serve as springs to yieldably resist opening and closing of the blades.

The improved knife has a pair of blades 1 which when closed extend from opposite ends of the handle with their cutting edges spaced from each other. The blades enter the handle through opposite side edge portions thereof which are open and each blade extends longitudinally of the handle from its tang or heel 2 and terminates in spaced relation to the tang and cutting edge of the other blade as shown in Figure 1 in order that there will be no danger of the blades becoming dulled by striking each other when closed. At opposite sides of the blades are disposed plates 3 which are preferably stamped from resilient sheet metal such as spring steel and therefore can be very cheaply made. The tangs project beyond the ends and sides of the plates as clearly shown in Figures 1 and 2.

These plates take the place of the side plates usually employed when forming a knife handle and have sufficient thickness to impart the necessary strength to the handle. Each plate is substantially oblong in shape and formed with arcuate end edges as shown in Figure 3 and near its ends is punched to form circular openings 4 located between slots 5 and 6 which extend longitudinally of the plate. The intermediate portion of each plate is cut from its opposite side edges as shown at 7 thereby forming a spring portion 8 having its leaves extending transversely of the plate and permitting the plate to be extended longitudinally when the blades are opened or closed.

Another object of the invention is to so form the face plates that their marginal portions will bear against side faces of the tangs of the blades and serve to prevent dust

Another object of the invention is to so connect the resilient side plates with the tangs of the blades that when a blade is opened or closed, the side plates will first be extended longitudinally and then contract and return to their original positions and serve very effectively to yieldably resist opening or closing of a blade without causing wear upon the tangs of the blades.

Another object of the invention is to permit longitudinal movement of the resilient side plates to be guided during expansion and contraction thereof by pins which, in addition to serving as guides for the resilient plates, also serve as fasteners for face plates of the knife handle.

Another object of the invention is to so form the face plates that their marginal portions will bear against side faces of the tangs of the blades and serve to prevent dust

Face plates 9, which may be formed of celluloid, metal or any other desired material, are disposed in covering relation to the resilient side plates 3 and correspond in length 5 to the distance between the outer ends of the heels or tangs 2 of the blades when closed. Flanges 10 which extend entirely about margins of the face plates project inwardly therefrom and since the face plates correspond in 10 width to the diameter of the tangs, the flanges will bear against marginal portions of the tangs.

Therefore when the pins 11 and 12 are inserted and heads formed at their ends to firmly hold the face plates in place, the resilient side plates will be disposed in pockets formed in the face plates by the flanges as shown in Figure 2 and permitted to easily slide longitudinally between the face plates and the 15 tangs of the blades. The pins 11 pass through openings formed centrally of the tangs of the blades in order to serve as pivots for the blades and are also engaged through the slots 5 of the side plates. The pins 12 20 pass through the slots 6 and together with the pins 11 serve to prevent transverse movement of the side plates and guide longitudinal movement thereof when they extend and then contract during opening or closing of 25 the blades.

The openings 4 of the side plates receive the end portions of pins 13 which extend through arcuate slots 14 formed in the tangs of the blades and by an inspection of Figure 35 1 it will be readily seen that when a blade is moved towards an opened position, a pin 13 will be moved longitudinally through the slot 14 of the blade thereby setting up a cam action which will cause the resilient side plates to be 40 extended longitudinally until the blade has been half opened and thereby yieldably resist opening of the blade. During the remainder of the opening motion, the resilient plates will contract and exert a pulling action 45 upon the pin 13 which will retain the blade in an opened position and yieldably resist movement of the blade towards a closed position. The same action takes place when either blade is opened and if so desired, one 50 blade may be opened before the other is closed.

While one blade has been shown at each end of the handle, it will be understood that additional blades may be provided or a knife formed with a single blade in which case a 55 filler disc will be used at the other end of the handle to take the place of the tang of a blade and retain the side plates in proper spaced 60 relation to each other.

What is claimed is:

1. A knife having pivotally mounted blades, and longitudinally expansible plates 65 extending between said blades with their end portions overlapping side faces of the blades

and yieldably resisting opening and closing of the blades.

2. A knife having pivotally mounted blades, and a longitudinally expansible spring extending between tangs of the blades 70 and overlapping side faces thereof whereby the spring will be expanded when either blade is moved to opened and closed positions and yieldably resist such movement.

3. In a knife, a handle having face plates, 75 blades having their tangs disposed between end portions thereof and provided with pivot pins extending through openings in the face plates, springs at opposite sides of said blades extending longitudinally of the face plates, 80 and cam connections between ends of the springs and tangs of the blades to expand the springs when the blades are opened and closed and yieldably resist such movement.

4. In a knife, a handle having face plates, 85 blades having their tangs disposed between end portions thereof and provided with pivot pins extending through openings in the face plates, plates of resilient material extending longitudinally of the handle at opposite sides of the blades and constituting longitudinally extensible springs, and means 90 to extend the plates when the blades are opened and closed and yieldably resist such movement.

5. In a knife, a handle having face plates, 95 blades having their tangs disposed between end portions thereof and provided with pivot pins extending through openings in the face plates, plates of resilient material extending longitudinally of the handle at opposite sides of the blades and having their intermediate portions cut to form longitudinally extensible springs, cam connections between 100 ends of the plates and tangs of the blades to extend the springs when the blades are opened and closed and yieldably resist such movement.

6. In a knife, a handle having face plates, 110 blades having their tangs disposed between the face plates and provided with pivot pins extending through openings in the face plates, plates of resilient material extending longitudinally of the handle at opposite sides of the blades and constituting longitudinally extensible springs, ends of the 115 plates being formed with longitudinally extending slots slidably receiving said pins to guide movement of the plates when the springs expand and contract, and cam connections between the resilient plates and tangs of the blades to expand the springs 120 when the blades are opened and closed and yieldably resist such movement of the blades.

7. In a knife, a handle having face plates, 125 blades having their tangs disposed between said plates and provided with pivot pins having their ends engaged extending through openings in the face plates, plates of resilient material extending longitudinally of 130

the handle at opposite sides of the blades and constituting longitudinally extensible springs, ends of the plates being formed with longitudinally extending slots slidably receiving said pins to guide movement of the plates when the springs expand and contract, arcuate slots being formed in the tangs of the blades, and pins carried by the resilient plates and engaged through the arcuate slots to exert pull upon the plates and cause the springs to be expanded when the blades are opened and closed and yieldably resist such movement of the blades.

8. A knife having movable blades, and a longitudinally expansible plate extending between said blades and operatively connected therewith for yieldably resisting opening and closing of said blades.

9. A knife having movable blades, face plates forming a part of the knife, and longitudinally expansible plates interposed between the face plates and blades and operatively connected with the latter for yieldably resisting opening and closing thereof.

25 10. A knife having a movable blade, a longitudinally expansible plate, and a pin and cam connection between the expansible plate and blade whereby the plate will expand when the blade is moved to opened or closed 30 positions and yieldably resist such movements.

11. A knife having pivoted blades, face plates having pockets, longitudinally expansible plates seated in said pockets, pin and 35 cam connections between the ends of the expansible plate and the pivoted ends of the blades whereby the plate will expand when the plates are moved to opened and closed positions and yieldably resist such movements, and means for guiding the expansible 40 plate during the expansion and contraction thereof.

In testimony whereof I affix my signature.
